UNITED STATES PATENT OFFICE.

EDWIN A. HARDISON, OF LOS ANGELES, CALIFORNIA, ASSIGNOR TO FIRST NATIONAL BANK & TRUST CO., OF SANTA PAULA, CALIFORNIA.

UNDERREAMER FOR WELL DRILLING.

Application filed March 27, 1922. Serial No. 547,179.

This invention relates to means for enlarging a hole in the earth below a casing through which such means must pass, and an object of the invention is to provide a tool 5 of this character which will be absolutely proof against the accidental displacement of any of its parts so that there will be no danger of loss in the hole.

Other objects are simplicity, strength, ease 10 of assembling, ease of setting, certainty of operation, ease of withdrawal into the casing, and ease of removing the cutters from and replacing them in the stock.

In this invention I provide simple cutters 15 and means to hold the cutters out of contact with the casing during the operation of going in and also of coming out of the hole.

An object is to avoid friction and wear on the cutters while the cutters are passing 20 through the casing.

I also provide practically non-breakable means for holding the cutters tightly in the stock, and to positively prevent any looseness, swinging or swaying of the cutters relative to the stock.

Another object is to increase the abutting surface between stock and cutters so as to minimize the battering and upsetting effect and to increase the life of the tool.

30 An object is to so construct the stock and the cutters and their shanks as to minimize the upsetting effect during operation.

Other objects, advantages and features of invention may appear from the accompanying drawings, the subjoined detail description and the appended claims.

The accompanying drawings illustrate the invention.

Figure 1 is a fragmental view of the underreamer and the lower part of the well casing as the same might appear during the operation of reaming a hole underneath the casing. Dash lines indicate the walls of the hole and broken lines in the upper part of the view indicate the position of the bits relative to the underreamer stock body when the tool is in the casing.

Fig. 2 is an enlarged view of the newly invented underreamer mainly in section 50 showing the underreamer in position to go through the casing either up or down.

Fig. 3 is a view analogous to Fig. 2 show-

ing the parts in position when the reamer is expanded below the casing.

Fig. 3^a is a cross section on line 3^a, Fig. 3. 55

Fig. 3^b is a cross section on line 3^b, Fig. 3.

Fig. 4 is an outside view in the scale of Figs. 2 and 3, of the underreamer at right angles to Fig. 1, a portion of the underreamer body being broken away to expose interior construction.

Fig. 5 is an enlarged elevation mainly in axial section on line x⁵, Fig. 3, of the underreamer.

Fig. 6 is a plan section on line x⁶, Fig. 2. 65

Fig. 7 is a plan section on line x⁷, Fig. 2.

Fig. 8 is a cross section on line x⁸, Fig. 3, looking up.

Fig. 9 is a cross section on line x⁹, Fig. 3, looking up. 70

Fig. 10 is a cross section on line x¹⁰, Fig. 3.

Fig. 11 is a fragmental view showing the spreader drawn out and the cutters in position to be withdrawn from the stock.

Fig. 12 is a view of the lower end of the 75 stock without cutters and spreader.

Fig. 13 is a longitudinal section of the body on line x¹³, Figs. 5 and 14.

Fig. 14 is a longitudinal section of the body on line x¹⁴, Fig. 13. 80

Fig. 15 is a perspective view of the spreader projecting trip latches.

Fig. 16 is a perspective disassembly of the cutters, the spreader and the assembling rod.

Arrows on the section lines indicate the 85 direction of sight.

The exterior of the stock 1 is mainly cylindrical with flattened sides, and its lower end is mainly in a plane at right angles to the axis of the stock. Said stock is provided with 90 a bore, a lower portion of which forms the cutter shank socket 2 that has parallel flat sides a to form guides for the cutter shanks and converges upwardly or is narrowed upwardly toward a common axis for a distance 95 to form seats b for the shanks of the cutters when said cutters are expanded. Said bore is widened to form shank-head accommodating recesses 3 above cutter shank-head retaining shoulders 4 provided in said socket 100 above said converging seats b. Above the recesses 3 the bore is reduced to form an elongated narrow spreader way 5, is again reduced to form a cylindrical rod way 5', and

is then enlarged to form a spring chamber 6 below which is a spring seat 7, see Fig. 5. The stock is threaded at its upper end as at 8 for connection through a sub 9 with a 5 drill stem 10, a fragment of which is shown in Fig. 2.

The cutters 11 are duplicates and are provided with shoulders having flat top faces 12 to abut the lower flat end portions of the 10 stock 1. Said cutters are provided with shanks 13 having enlarged tips forming on the outer faces of the shanks, heads 14 constructed to hook over the shoulders 4 when the shanks are spread apart; and the conical outer sides b' of the shanks 13 are seated against the concave taper seats b .

The edges c of the shanks 13 are parallel to each other and snugly fit the shank ways formed by the parallel sides a of the socket.

20 The inner faces of said cutters are provided with recesses 15 above which are expanding faces 16 extending along the lower portion of the shanks 13, for a short distance; and above said faces 16 the inner faces 25 of the shanks are cut away as at 17.

The expander is adapted to be moved up and down between the inner faces of the cutters 11 and their shanks, and is adapted at one position to hold the shanks with their 30 heads 14 hooked over the shoulders 4, and at a higher position to expand the cutters, and at a lower position to allow the heads to be unhooked from the shoulders.

35 The expander comprises a block 18 movable up and down between the inner faces of the cutters 11 and into and from the space between the shanks of said cutters, said block is adapted to be accommodated in the notch 15 to allow the cutters to collapse.

40 Said block is also adapted to engage the expanding faces 16 to hold the cutters in expanded position shown in Fig. 3. The expander block 18 is supported by a bar comprising a flat blade 19, a spreading wedge 20, connection 21, and the rod body 22 around which is arranged the spring 23 adapted to rest on the seat 7, and retained 45 on said rod by a hollow head formed as a nut 24 screwed onto said rod above the 50 spring, to be acted upon by the spring to cause the wedge 20 and block 18 to hold the cutters 11 in expanded position as shown in Figs. 1 and 3. Said head 24 is recessed at the 55 top as indicated at 25 to accommodate retaining fingers 26 that extend into said recessed head from the spring compressing and spreader releasing trip blocks 27.

The stock is provided with lateral ways 28 formed internally as longitudinal slots 29, and externally as notched bearing faces as at 60 30, 32 and 33.

The trip blocks 27 comprise webs 34 connected by resilient means as springs 35 that tend to draw the blocks together. Said trip

blocks also have runners 36 each of which 65 has a bearing lug 37 at each end and a recess 38 therebetween adapted to embrace the intermediate face 31 when the lugs at 37 are in the recesses at 30 and 32. Said lugs are also so spaced and arranged relative to the 70 faces 31 and 32 that when the blocks 27 are at the top of the ways 28, and the spreader is up, and the cutters held expanded by the spreader as shown in Fig. 3, there will be no 75 looseness of parts; and the runners 36 project from the sides of the stock 1 ready to be held by contact with the shoe 39 of the casing 39' so that upward movement of the stock through the casing will force the spreader down, thus allowing the lower end 80 of the cutters to swing toward the produced axis of the stock as indicated in Fig. 2.

When the faces 31 and 33 have thus been removed from the lugs 37 and said lugs enter the notches 30 and 32 the blocks will be 85 slid into the stock by pressure of the shoe and can then pass through the shoe and the casing. The retaining fingers 26 in the hollow head 24 normally hold the blocks in 90 the stock but may be removed when the spreader is in the depressed position shown in Fig. 2, and the blocks are raised to bring the fingers above the top of said head.

The spreader is provided with a threaded 95 socket 40 into which a retracting rod 41 may be screwed to enable the workman to retract the spreader against the pressure of the spring 23.

The wedge 20 and the shanks and socket 100 walls and the shoulder 4 are so proportioned that when the spreader is fully retracted as in Fig. 11, the cutters may be so swung as to release their heads from the shoulder 4; but at all other positions of the spreader the heads hook over said shoulders. 105

The assembling rod 42 passed through the holes 43 in the stock and loosely fitted in the holes 44 in the cutters and the slot 45 in the spreader serves to retain the cutters in the 110 operation of assembling and must be removed in order to remove the cutters and the spreader.

Longitudinal grooves 46 in the cutter 115 socket accommodate the guides 47 on the edges of the spreader to prevent looseness of the spreader.

The notches 48 accommodate portions of the cutters. 49 indicates drainers for the spring chamber.

When it is desired to remove the cutters, 120 the block and spreader 18, 20, is drawn down into the position shown in Fig. 11, so that the recesses 17 accommodate the spreader and allow the shanks to be brought sufficiently together to allow the heads 14 to be 125 released from the shoulders 4 at the upper part of the socket.

The socket is gradually tapered as shown,

and the cutter supporting shanks are correspondingly elongated so that the center of gravity of the cutters when expanded is but slightly displaced from the line of direction of the collapsed cutters, and the force required to swing the cutters from collapsed to expanded position is minimized.

I claim:

1. In an underreamer having a stock with a socket at its lower end and having cutters provided with shanks adapted to engage said socket; a spreader adapted in one position to separate the shanks to cause the same to engage with the socket and to expand the cutters, and in another position to hold the shanks apart and allow the cutters to be collapsed; a spring adapted to draw said spreader up to spread the shanks and the cutters apart; means in the stock to support the spring; means on the spreader whereby the spring operates to separate the shanks; and runners projecting from the stock and adapted to be held by a casing while the stock is being withdrawn therethrough and to hold the spreader while the stock is drawn upward to escape the cutters and to allow the cutters to collapse; there being ways in the stock to allow the runners in one position to be retracted into the stock to allow the runners and stock to pass through the casing while the spreader is in position to hold the shanks engaged with the stock while the cutters are collapsed.
2. In an underreamer of the character set forth having a stock and cutters in the stock; a spreader having upon its upper end a hollow head, a spring acting on said head to lift the spreader; there being slots in the stock, and spring compressing runners in said slots provided with fingers extending into the cavity of said hollow head, said fingers being adapted to prevent the runners from being removed from the slots, and movable along and in said slots by contact with a casing shoe.
3. In an underreamer of the character set forth comprising a stock and cutters in the stock; a spreader between the cutters having upon its upper end a hollow head; a spring acting on said head to lift the spreader; there being slots in the stock; runners in said slots provided with fingers extending into the cavity of said hollow head; springs to retract the runners into the stock; and means to hold the runners extended in position to engage with the shoe of a casing when the tool with expanded cutters is drawn up.
4. An underreamer comprising a stock having a bore constituting a spring chamber, and at its lower end, a socket; and having a spring seat between said socket and spring chamber; a spring in said spring chamber and seated on said seat; a spreader in said socket and having a rod extended in-
5. An underreamer comprising cutters and having a stock provided with a bore, the lower portion of which bore forms a cutter-shank socket that has parallel flat sides to form guides for cutter-shanks and that is upwardly narrowed a distance to form seats for such shanks when said cutters are expanded; said bore being widened to form shank head accommodating recesses above cutter-shank head retaining shoulders; said bore being reduced above the recesses to form a spreader way, and again reduced to form a rod-way, and then enlarged to form a spring chamber below which is a spring seat; said bore extending from end to end of the stock and said stock being adapted at its upper end for connection with a drill stem.
6. An underreamer comprising cutters and having a stock provided with a bore, the lower portion of which bore forms a cutter-shank socket that has parallel flat sides to form guides for cutter-shanks, and that is upwardly narrowed a distance to form seats for the shanks of the cutters when said cutters are expanded; said bore being widened to form shank-head accommodating recesses above cutter-shank head retaining shoulders; said bore being reduced above the recesses to form a spreader way, and again reduced to form a rod-way and then enlarged to form a spring chamber below which is a spring seat; said bore extending from end to end of the stock and said stock being threaded at its upper end for connection with the drill stem; said cutters having shanks to seat in said shank seats and heads to engage said shoulders; a spreader in the spreader way and adapted to be moved between the shanks to hold said shanks with the heads engaging the shoulders; said spreader being provided with a rod body extending into said spring chamber; a spring seated on the spring seat and surrounding said rod body within the spring chamber; a nut on said rod supported by said spring; said stock being provided with lateral ways formed internally as longitudinal slots and externally as notched bearing faces; trip blocks comprising webs and having runners each of which has a

bearing lug at each end and between such lugs a recess adapted to embrace a face between said notches when said lugs are seated in said notches, and so spaced and arranged relative to the faces that when the blocks are at the top of the ways and the spreader is up, and the cutters held expanded by the spring, there will be no looseness of parts, and the runners project from the sides of the stock ready to be held by contact with the shoe of the well casing on upward movement of the stock through the casing to hold the spreader down, as the stock rises, thus allowing the lower end of the cutters to swing toward the produced axis of the stock to collapse the cutters.

7. In an underreamer provided with a stock having a bore, with a cutter socket and longitudinal slots, said underreamer being also provided with cutters, a spreader, and a rod for said spreader; a head for said rod provided with a cavity; a spring supporting said head; trip blocks in said slots and provided with fingers extending into the cavity of said head; said blocks running in said slots and having lateral movement therein and provided with fingers inserted into the cavity and adapted to prevent the blocks from being removed from the slots.
8. In an underreamer provided with a stock having a bore, a cutter socket and longitudinal slots and also cutters and a spreader and a rod for said spreader; a head for said rod provided with a cavity, a spring supporting said head; trip blocks mounted in said slots and provided with fingers extending into the cavity of said head; said blocks running in said slots and having lateral movement therein and provided with fingers inserted into the cavity and adapted to prevent the blocks from being removed from the slots; and springs connecting said blocks to draw the same toward each other.
9. In an underreamer having cutters with cutter-supporting shanks; a stock provided with a socket forming seats for the cutter-shanks and having longitudinal grooves in its opposite sides between said seats; and a spreader extending into the grooves and

arranged between the cutter-shanks to hold the same in engagement with the stock.

10. In an underreamer having cutters with shanks; a stock provided with a socket forming seats for the cutter-shanks and having longitudinal grooves in its opposite sides between said seats; a spreader extending into the grooves and arranged between the cutter-shanks to hold the same in engagement with the stock; a spring carried by the stock to hold the spreader in engagement with the cutter-shanks during reaming operation and means operable in opposition to the spring to move the spreader to permit the cutters to be collapsed to withdraw the underreamer.

11. In an underreamer comprising cutters having shanks in a socket, means adapted in one position to hold the shanks apart to engage the socket and also to expand the cutters; and in another position to hold the shanks apart and allow the cutters to be collapsed; and in a third position to allow the shanks to be brought together sufficiently to withdraw them from the socket.

12. An underreamer comprising a stock having a socket in its lower end and shoulders at the outer sides of the upper part of said socket; cutters having heads to engage said shoulders; and a spreader between said cutters; said spreader being adapted in one position to hold the heads over the shoulders and adapted in another position to allow the heads to escape the shoulders.

13. An underreamer comprising a stock having a socket in its lower end and shoulders at the outer sides of the upper part of said socket; cutters having heads to engage said shoulders; and a spreader between said cutters; said spreader being adapted in one position to hold the heads over the shoulders and adapted in another position to allow the heads to escape the shoulders; and a spring to hold the spreader in spreading position.

In testimony whereof, I have hereunto set my hand at Los Angeles, California, this 13th day of March, 1922.

EDWIN A. HARDISON.
